UNITED STATES PATENT OFFICE.

JOHN JUHASZ, OF NEW YORK, N. Y.

CHARGE-FORMING DEVICE FOR INTERNAL-COMBUSTION ENGINES.

Application filed April 28, 1925. Serial No. 26,364.

The present invention relates to charge-forming devices for internal combustion engines, and more particularly to means for delivering a heated auxiliary air stream to the carbureter.

The main object of the invention is to provide a carbureter wherein the flow of heated auxiliary air thereinto is controlled by the throttle thereof.

Another object of the invention is to so construct the controlling means that the heated auxiliary air is introduced at an angle to the flow of the combustible mixture, in order to induce turbulence, which, in conjunction with the high heat, tends to break up any globules of fuel before they enter the intake manifold of the engine.

A further object of the invention is to so construct the controlling means that only a small stream of heated air is introduced into the carbureter during the entire range of the throttle movement, and the bulk of the heated air is conducted into the carbureter within certain limits of the throttle movement.

A still further object of the invention is to produce a charge-forming device of the type mentioned which is simple in construction, efficient in operation and capable of manufacture on a commercial scale, or in other words one which is not so difficult to make as to be beyond the reasonable cost of such a device.

Another object of the invention is to provide an air heating device, which utilizes the heat of the exhaust gases of the engine.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawings, in which:

Figure 1 is a side elevation of an internal combustion engine, showing in longitudinal section the intake and exhaust manifolds thereof; Fig. 2 is a central vertical section taken through a charge-forming device, con-

structed in accordance with the present invention; Fig. 3 is a section taken on line 3—3 of Fig. 1, the throttle of the carbureter being removed; Fig. 4 is a side elevation of the throttle of the carbureter; Fig. 5 is a top elevation of the said throttle; Fig. 6 is a section taken on line 6—6 of Fig. 3, with the throttle in position on the carbureter, on a larger scale; Fig. 7 is a section similar to the one shown in Fig. 6, with the throttle in another position; and Fig. 8 is a section taken on line 8—8 of Fig. 3, with the throttle in position on the carbureter, on a larger scale.

Generally speaking the invention consists of providing in the exhaust manifold of an internal combustion engine an air heating tube and connecting the same to a carbureter to furnish a stream of heated auxiliary air, the flow of heated air through the carbureter being controlled by the carbureter throttle in such a manner that a small quantity of heated air is admitted into the carbureter throughout the entire range of movement of the throttle, and the bulk of the heated air is admitted only throughout the ordinary driving range.

Referring now to the drawings, the numeral 10 indicates an internal combustion engine, on which is mounted an exhaust manifold 11 and an intake manifold 12. To the intake manifold is connected a carbureter 13 in the usual manner. The carbureter herein described is of the multi-jet type, it comprising a casing 14, in the side of which is formed an opening 15, forming the air inlet to the carbureting chambers, an opening 16 being provided in the upper face of the casing, constituting the outlet through which the charges, formed in the chambers, pass to the intake manifold. The air inlet communicates with a plurality of, in the present case three, Venturi passages, denoted by the numerals 17, 18 and 19, which form independent carbureting chambers, into each of which projects a fuel nozzle 21. These nozzles may be of any suitable construction, they communicating with a float chamber 22 of any approved type.

Above the carbureting chamber is formed on the casing a horizontally extending hollow cylindrical portion 23, the ends of which are closed by heads 24 and 25. On these heads are formed bearings 26 for the journals 27 of a cylindrical body 28, which is located within and snugly fits the cylindrical portion of the carbureter casing. This

cylindrical body constitutes a throttle valve, as will hereinafter appear. The throttle is provided with three bores, denoted by the numerals 30, 31 and 32. The bore 32 is cylindrical throughout its length and extends diametrically through the body of the throttle, it being adapted to co-operate with the carbureting chamber 19. The bores 30 and 31 intersect one another (Fig. 8), they having separate inlets 33 and 34, respectively, but a common outlet 34'. The bores 30 and 31 are disposed at the side of the bore 32, their inlets co-operating with the carbureting chambers 17 and 18, and their common outlet with the mixture outlet of the carbureter casing.

The casing of the carbureter is so shaped immediately above the cylindrical portion thereof that, when the throttle is turned, the discharge ends of the bores therein are decreased or increased, depending upon the direction in which the throttle is turned. Attention is, however, called to the fact that provision is made in the side of the casing above the cylindrical portion thereof that the discharge opening 34' of the bores 30 and 31 is somewhat uncovered when the throttle is in its fully closed position (Fig. 8), so as to admit of a flow of air past the fuel nozzle in the chamber 17, to furnish the proper amount of combustible mixture for the motor for idling. The throttle may be actuated in any suitable manner by means not shown, means being also provided (not shown), for limiting the movement of the said throttle.

A pipe 36 of heat conducting material, such as metal, is extended through the exhaust manifold, the inlet end 37 of the said pipe being projected through the closed end 40 of the exhaust manifold. The pipe is extended within the exhaust manifold practically for the length of the latter, and is then led through the said manifold at 38 and connected in any suitable manner with an aperture 39 in the head 25 of the carbureter. This aperture communicates with an arc-shaped pocket 40 in the inner face of the head 25. In the throttle is formed a passage 41, the inlet end 42 of which terminates in that end face 43 of the cylindrical throttle body which contacts with the head 25 so as to make an air-tight fit. The outlet end 44 of the passage 41 terminates in the leading edge 45 of the combined discharge opening 34' of the bores 30 and 31 of the throttle body. The aperture 39 and the pocket 40 are disposed in the path of the inlet end 42 of the passage 41, so that, throughout the entire range of movement of the throttle, the passage 41 is in communication with the pipe 36. In the throttle is furthermore formed a passage 46, the inlet end 47 of which terminates in the end face 43 of the throttle, while its outlet end 48 terminates in the cylindrical face of the said throttle a

substantial distance in front of the leading edge 49 of the discharge end of the bore 32 in the throttle body (Fig. 5). The cross-sectional area of the passage 46 is considerably larger than the cross-sectional area of the passage 41, for a purpose hereinafter to be described. The inlet end 47 of the passage 46 is adapted to communicate with the aperture 39 in the head 25.

The operation of the charge-forming device is as follows: When the throttle is in its closed position, shown in Fig. 8 of the drawings, the carbureting chambers 18 and 19 do not communicate with the carbureter outlet 16. The carbureting chamber 17 communicates, however, through the bore 30 and the common outlet 34' of the last-mentioned bore and the bore 31 with the said carbureter outlet, a minimum opening being provided, sufficient to permit of a flow of air past the fuel nozzle in the carbureting chamber 17 to furnish combustible mixture for the motor to run idle, that is to say, to run without load. For sometime, during the movement of the throttle in the direction of the arrow shown in Fig. 8 toward opening position, the bore 30 communicates with the carbureting chamber 17 alone, more particularly until the leading edge of the inlet to the bore 32 reaches the rear edge of the carbureting chamber 19. The bore 31 is so positioned in the throttle in relation to the bores 30 and 32 that the carbureting chamber 18 is cut in after the chamber 19 has been opened. Thereafter the chamber 17 communicates with the throttle passage 31, so that, when the throttle is brought to fully open position, all of the carbureting chambers are in action. Inasmuch as the passage 41 is constantly in communication with the hot air pipe 36, a small quantity of hot air will be caused to flow into the carbureter during the entire range of the throttle movement by the vacuum in the intake-manifold. As appears from Fig. 8 of the drawings, the passage 41 communicates with the carbureter, above the throttle, when the latter is in its fully closed position. The said passage also communicates with the carbureter while the throttle is moved toward and to fully open position. It is to be noted, however, that when the throttle is in its closing position, as shown in Fig. 7 of the drawings, the inlet end 47 of the passage 46 does not communicate with the aperture 39 in the head 25 of the carbureter casing, so that heated air will not flow into the carbureter through the last-mentioned passage. When the throttle is shifted toward opening position, the inlet end 47 of the passage 46 is brought into communication with the aperture 39, so that heated air will flow through the passage 46 into the carbureter casing. The inlet end 47 of the passage is gradually uncovered, so that the amount of air flowing

through the passage 46 increases with the throttle opening movement. Inasmuch as the outlet end 48 of the passage 46 is disposed a substantial distance in front of the leading edge 49 of the outlet end of the bore 32, the flow of heated air through the passage 46 is gradually cut off, it being entirely cut off before the throttle is fully opened. From the foregoing it appears that a small quantity of heated air is admitted into the carbureter during the entire range of throttle movement. This quantity of heated air is gradually increased up to a certain point of the throttle movement and is then again gradually decreased before the throttle is in its fully open position.

The auxiliary air stream is heated to a high temperature by the exhaust gases, and is introduced into the main intake stream 20 at an angle to the flow of the latter, as clearly appears from the drawings. A turbulence is thus induced in the main intake stream, which, in conjunction with the high heat, breaks up any globules of fuel 25 just before they enter the intake manifold. The amount of heated air admitted into the carbureter is, as described above, dependent on the amount the throttle is open and proportionate thus to the speed the engine is running at. The heated auxiliary air is thus properly proportioned to the flow of fuel to the engine, heating the atomized raw fuel and converting the atomized fuel into a dry gaseous explosive mixture, so that the 30 mixture passing into the engine will have a greater explosive force. Condensation of the fuel is also practically eliminated. Actual experiments have shown a decided 35 increase in car mileage and a decided decrease in the carbon monoxide contents of the exhaust gases. From this it would appear that a more perfect combustion is obtained in the engine than when a cold auxiliary air stream is admitted into the explosive mixture.

It is to be noted that, while herein a specific multi-nozzle carbureter has been described, the invention is applicable to others just as well, the invention residing mainly in 50 the provision of a throttle which controls the flow of heated auxiliary air into the carbureter, gradually increasing the amount of

heated air up to a certain point of the throttle opening and then gradually decreasing the same.

55

What I claim is:

1. In an internal combustion engine, the combination with an intake-manifold, of a carbureter including a casing having an air inlet receiving direct from the atmosphere 60 the main supply of air and a combustible mixture outlet communicating with said intake-manifold, a plurality of carbureting chambers communicating with said inlet, a cylindrical throttle interposed between said carbureting chambers and said outlet provided with bores through which communications are adapted to be established gradually and in succession between said carbureting chambers and said outlet, and a 65 conduit for supplying heated auxiliary air to said carbureter, said throttle being provided with a passage constantly in communication with said conduit and with said carbureter outlet, said throttle being furthermore provided with a passage in communication with said conduit and with said combustible mixture outlet only during part of its movement.

2. In an internal combustion engine, the combination with an intake manifold, of a carbureter including a carbureting chamber communicating with said manifold and receiving direct from the atmosphere the main supply of air, said carbureter including a 80 throttle, a conduit for supplying heated auxiliary air to said carbureter, and means associated with said throttle for controlling the flow of heated auxiliary air to said carbureter, said controlling means admitting 85 heated auxiliary air into the carbureter during the entire range of the throttle movement and permitting of a gradual increase of the auxiliary air up to a certain point of the throttle movement toward opening position and then gradually decreasing the same, said controlling means being wholly embodied in said carbureter and partly constituted by said throttle.

Signed at New York, in the county of 90 New York, and State of New York, this 24th day of April, A. D. 1925.

JOHN JUHASZ.
